R. M. SPARKS.

KNIFE AND SCISSORS SHARPENER,
APPLICATION FILED OCT. 11, 1916.

1,234,945.

Patented July 31, 1917.

UNITED STATES PATENT OFFICE.

ROLLO M. SPARKS, OF TWIN FALLS, IDAHO.

KNIFE AND SCISSORS SHARPENER.

1,234,945.

Specification of Letters Patent. Patented July 31, 1917.

Application filed October 11, 1916. Serial No. 125,031.

To all whom it may concern:

Be it known that I, ROLLO M. SPARKS, a citizen of the United States, residing at Twin Falls, in the county of Twin Falls and State of Idaho, have invented certain new and useful Improvements in Knife and Scissors Sharpeners, of which the following is a specification.

This invention relates to devices for 10 sharpening knives, scissors, and similar tools, and consists in certain novel features which are illustrated in the accompanying drawings and will be hereinafter first fully described and then more particularly pointed 15 ed out in the appended claims.

In the drawings:

Figure 1 is a side elevation partly broken away and in section of a device embodying my invention;

20 Fig. 2 is a front elevation of the same;

Fig. 3 is a detail perspective view of a bracket by which the grinding shaft is held in place.

In carrying out my invention, I employ 25 a standard 1 which is provided with a recess 2 in its rear side, near its lower end, whereby it may be fitted over the edge of a table, as indicated at 3. In the lower end of the standard, I mount means for locking the 30 same on the table and in the present drawings, I have illustrated a clamping screw 4 so disposed that it may be turned to bear against the under side of the table and force the same against the upper wall of the notch 35 or recess 2.

The upper end of the standard is formed to present two jaws 5 and 6 having their inner walls flared upwardly and upon one of the said jaws, at the upper end thereof, 40 is formed an inclined table 7, as clearly shown. The abrading body 8, which may be a stone or a file, is disposed between the jaws 5 and 6 and is carried by a grinding shaft 9 which is journaled at its lower end 45 in the standard 1 and has secured to its lower end a pinion 11 arranged within a notch or recess 12 in the standard and meshing with an idler 13 which is also housed within said recess and is retained in place 50 by a pintle 14 inserted through the said recess from the lower end of the space between the jaws 5 and 6, as clearly shown in Fig. 1. A driving wheel 15 is mounted in any preferred manner upon the front of the stand- 55 ard and meshes with the pinion 13, as shown, the said wheel 15 being provided with a

handle 16 so that it may be readily rotated. The abrading body 8 is provided with an angular central opening or bore which fits around the correspondingly shaped portion 60 of the driving shaft 9, so that the rotation of the shaft will be imparted directly to the said abrading body, and to prevent the stone or file wearing away the standard, a washer or collar 17 is fitted upon this shaft between 65 the lower end of the abrading body and the standard. To prevent vibration of the shaft 9 and the body mounted thereon, I provide a bracket 18 which is secured upon the side of the standard and engages over the upper 70 extremity of the shaft. This bracket is preferably a metal strap having its upper extremity extending transversely over the abrading body and engaging the end of the shaft 9 so as to form a bearing for the same. 75 The bracket is offset from the standard, as shown clearly in Figs. 2 and 3, and its lower portion is disposed to bear directly against the side of the standard, being constructed with a longitudinal slot 19 above its lower 80 extremity and with a notch 20 in said extremity. The notch 20 engages over a pin or stud 21 inserted in the side of the standard and a thumb screw 22 is inserted through the slot 19 into the standard so that the 85 bracket will be retained in place. When it is desired to remove the abrading body so as to clean the same or supply a new body, it is only necessary to withdraw the thumb nut 22, after which the bracket may be lifted 90 from its engagement with the stud or pin 21 and the end of the grinding shaft.

The operation of the device will be readily understood. In sharpening a knife, the knife blade is held against the jaw 5 or the 95 jaw 6 with the edge downward, so that it will bear against the abrading body 8 and while the blade is held in this position, the driving wheel 15 is rapidly rotated, thereby causing the abrading body to rotate against 100 the blade and quickly form the desired edge thereon. The inclined or beveled faces of the jaws 5 and 6 form firm supports for the knife blade and permit the operator to readily obtain the desired bevel for the cutting 105 edge. In sharpening scissors or shears, the blade is placed upon the inclined table 7 with the edge bearing upon the abrading body and the rotation of said body will then quickly form the desired bevel on the edge 110 of the blade.

My device is exceedingly simple in the

construction and arrangement of its parts and may be very cheaply manufactured and very readily secured in position and operated and in operation will be found highly efficient for the purposes for which it is designed.

Having thus described the invention, what is claimed as new is:

1. A device for the purpose set forth comprising a standard having upstanding jaws rising from its upper end and provided with upwardly flared opposed inner faces, a vertically disposed grinding shaft journaled at its lower end in the standard and rising therefrom between said jaws, an abrading body secured on said shaft between the jaws, a train of gearing housed within the standard and operatively connected to the lower end of the grinding shaft, and an actuating member mounted externally on the standard and arranged to impart motion to said train of gearing.
2. A device for the purpose set forth com-

prising a standard provided at its upper end with a blade support, a vertically disposed grinding shaft journaled in the standard adjacent the said support, an abrading body secured upon said shaft, means on the standard for rotating said shaft, and a bracket having its lower end secured to the standard and its upper end fitting over the said grinding shaft.

3. A device for the purpose set forth comprising a standard, a grinding shaft mounted thereon, means on the standard for rotating said shaft, a bracket having an offset portion and having its upper end engaging the grinding shaft and its lower end provided with a notch at its extremity and a longitudinal slot above said extremity, a pin or stud on the standard engaged in said notch, and a retaining device inserted through said slot into the standard.

In testimony whereof I affix my signature.

ROLLO M. SPARKS. [L.S.]
